UNITED STATES PATENT OFFICE.

FRANK W. GRISWOLD, OF ROGERS, MINNESOTA.

YIELDING SELF-ARIGHTING SAFETY LAMP POST.

Application filed August 2, 1922. Serial No. 579,290.

To all whom it may concern:

Be it known that I, FRANK W. GRISWOLD, a citizen of the United States, residing at Rogers, in the county of Hennepin and State 5 of Minnesota, have invented certain new and useful Improvements in Yielding Self-Arighting Safety Lamp Posts; and I do hereby declare the following to be a full, clear, and exact description of the invention, 10 such as will enable others skilled in the art to which it appertains to make and use the same.

This invention relates to means for supporting a lamp post or similar post adapted 15 to be placed in or at the sides of a street or pavement located where it is possible for the same to be struck by traffic vehicles. With the large numbers of automobiles operating in cities it is becoming a very frequent occurrence for lamp posts and signal posts to be struck by such automobiles and broken off. This constant breakage of lamp posts and 20 similar structures results in a great expense to the city or concern installing and replacing the same.

It is an object of this invention, therefore, to provide such a post having a supporting means permitting the post to swing when the same is struck, such a swinging movement 25 permitting the post to swing to substantially a horizontal position.

It is a further object of the invention to provide such a supporting means comprising a plurality of pivoted sections adapted 30 to be raised when the post is swung.

It is a still further object of the invention to provide extensible means for holding the post in upright position and returning the same to such position together with guiding means insuring that the post will properly contact one of said pivoted sections. 40

These and other objects and advantages of the invention will be fully set forth in the following description made in connection with the accompanying drawings in which like reference characters refer to the same parts throughout the different views, and in which,

Fig. 1 is a partial plan view of the device; 50 Fig. 2 is a view in side elevation of part of the supporting means;

Fig. 3 is a view in vertical section of the device with the top portion of the post broken away; and

Fig. 4 is a view in front elevation of the 55 complete post and supporting means, the same being on a reduced scale.

Referring to the drawings, a post 1 is shown which may be an ordinary lamp post, signal post or similar structure. The post 60 is secured at its lower end in a member 2 substantially of ball or spherical shape, which member has a lug 3 projecting centrally from its lower side. The supporting means for said members comprises a casting including a member 4 which will preferably be a casting and which is shown as of substantially square or rectangular shape. This member 4 is adapted to be secured in the ground or in the pavement of the thoroughfare by suitable foundation bolts 5 depending from and extending through the 70 corners of said member 4. The member 4 is provided with recesses at the four sides thereof in which are disposed pivoted members 5. The side portion of these members converge along radial lines and they have curved front portions substantially contacting with the ball 2. These front portions of the members are slotted and portions 6 of 75 flexible or resilient material such as rubber fabric, are inserted in these slots and project from the members into close contact with the ball 2. The members 5 are pivoted to the member 4 by pins 7 secured in one of 80 said members and pivotally mounted in the other. The corners of the member 4 are provided with cap plates 8 adapted to be bolted thereto to facilitate the placing of the members 7. Depending from the member 4 85 beneath the members 5 are ribs or lugs 9, and bolts 10 extend through these lugs and form the attaching bolts for a casing 11 of inverted frusto-conical shape, which casing 90 extends around the outside of the ribs 9 and encloses the same. The inner ends of the bolts 10 are formed with eyes for a purpose 95 to be later described. The casing 11 has a channel member 12 bolted thereto on the outside thereof with its flanges depending 100 therefrom. The bolt 13 securing the members 11 and 12 together is also formed as an eye-bolt on its inner portion and the same is engaged by one end of an extensible spring 14, the upper end of which is secured 105 in a pipe or tube 15, which latter is formed with a hook adapted to be secured through an aperture in the projection 3 of ball 2.

The member 15 has a plate 16 secured thereto adjacent its top end provided with a plurality of spaced holes, and extensible springs 17 have one of their ends engaged through 5 the said holes in said plate and their other ends engaged in the inner ends of the bolts 10. The member 4 is also provided with inwardly projecting equally spaced tapered or wedge shape members 18 having their 10 central axes disposed in alinement with the adjacent edges of the members 5. The members 18 are curved downwardly on their top surfaces and form the support normally supporting the ball 2 when the same is in 15 upright position.

From the above described structure it is seen that normally the post 1 is held in upright position by the springs 14 and 17 and the members 5 are in horizontal position 20 in contact with the member 4. The top of members 4 and 5 are preferably arranged flush with the surface of the pavement or ground of the thoroughfare. If the post 1 be struck by a vehicle or other heavy member, the same will swing to one side and extend the tension springs 14 and 17. The post will fulcrum against the edge of one 25 of the members 5 and there will be a considerable slipping movement along said 30 edge owing to the resistance of the attaching springs. As the post swings to one side, the downwardly extending projection 3 will be swung laterally and engage under one of the members 5, as illustrated in dotted lines in Fig. 3. The members 18 will 35 insure that this projection will always be guided into proper engagement with the under front edge of said members 5. As the post swings, said member 5 will be lifted 40 and room thus provided for passage of member 15 and also the end of one of the springs 17 should the post be swung sufficiently to one side. After the pressure is removed 45 from the post 1 the same will be returned to its upright position by action of springs 14 and 17 and the members 5 will drop into the position shown in Fig. 3, by gravity. This gravity action of the members 5 is, 50 of course, equivalent to having the same mounted with tension means urging them to normal position.

The chamber formed by members 4 and 11 is liquid tight and in practice the same is filled with oil to the level indicated in 55 Fig. 3. This keeps the parts free from rust and stiffness and insures a successful operation of the springs and connections.

From the above description it is seen that 60 applicant has provided a simple and efficient means for preventing injury to a lamp post or similar structure when the same is struck by a moving vehicle or other object. The post, as stated, can be pushed to substantially parallel position with the 65 pavement and will yet be uninjured. The

parts of the device are few and can be made sufficiently rugged to withstand heavy traffic. The parts are also designed to be securely held in a pavement and will form a part or continuation thereof.

It will, of course, be understood that various changes may be made in the form, details and arrangement of the parts without departing from the scope of applicant's invention, which, generally stated, consists in the matter shown and described and set forth in the appended claims.

What I claim is:

1. A lamp post or similar structure having in combination, an upstanding post, a ball secured to the lower end thereof, extensible means for holding the ball and post normally in upright position, and a plurality of pivoted members flush with the ground or pavement surface adjacent the post and adapted to be independently lifted when the post is swung to inclined position.

2. A lamp post or similar structure having in combination an upstanding post, a ball secured to the lower end thereof, having a downwardly extending central projection on its underside, extensible resilient means connected to said projection for holding the ball and post in upright position, and a plurality of hinged members having 95 their top surfaces horizontal and pivoted on horizontal axes spaced outwardly of said ball adapted to be independently contacted and raised by said projection.

3. A lamp post or similar structure having in combination an upstanding post, a ball secured to the base of the same having a depending projection, spaced supporting means for said ball, a plurality of members surrounding said ball and contacting therewith at their forward edges pivoted on horizontal axes spaced outwardly of the ball, extensible means for holding the ball and post in upright position, said supporting means forming guiding means for said projection to guide the same into contact with one of said pivoted members when the post is swung to inclined position.

4. A lamp post or similar structure having in combination an upstanding post having a ball secured to its lower end, said ball having a central downwardly projecting attaching means on its lower underside, a plurality of members surrounding said ball and pivoted on axes disposed outwardly thereof, extensible means for holding the ball in upright position, and means for guiding said attaching means into contact with one of said members when the post and ball are swung to inclined position.

5. A lamp post structure having in combination an upstanding post having a ball secured to the lower end thereof and a plurality of pivoted members surrounding said ball and contacting therewith at their for-

ward ends, said members having radially extending adjacent edges and being pivoted on axes disposed outwardly of said ball.

6. A lamp post or similar structure having in combination, a lamp post having a substantially spherical member secured at its lower end, means for supporting said members comprising a casing having a horizontal top surface, a plurality of hinge members surrounding said spherical member and having their front edges substantially in contact therewith, and flexible means carried in said front edges of said members contacting said spherical member.

10 7. A lamp post or similar structure having in combination an upstanding post having a substantially spherical member secured to its lower end, said member having a central downwardly extending attaching means on its underside, a casing having spaced supporting means for said spherical member, and a plurality of hinged members at the top of said casing surrounding said spherical member and contacting there- 25 with at their forward edges, and extensible means for holding said post and spherical member in normal position and for returning the same to normal position after being swung from upright position.

15 8. A lamp post or similar structure having in combination, a casing including an inverted frusto-conical chamber at its lower side, said casing being adapted to be set into the pavement or a roadway, means for attaching the casing to said pavement, an up- 30 standing post having a ball secured to its lower end supported in said casing, said ball having a downwardly extending attaching means at its underside, a rigid member

swiveled to said attaching means and depending therefrom, a spring secured to said rigid member and to the bottom of the casing, and a plurality of substantially horizontal tension springs secured to said rigid member adjacent the bottom of said ball and 45 secured at their other ends to the sides of the casing.

9. A lamp post or similar structure comprising an upstanding post having a ball secured to its lower end, means for supporting said ball and post for swinging movement, a substantially vertical extending spring enclosed in a cylindrical casing, a circular collar near the top of said casing and a plurality of horizontally radiating 50 springs secured at intervals to said collar operative in co-operation with said vertical spring to normally hold said ball in and return the same to normal position.

10. A lamp post or similar structure having in combination, an upstanding post, means adjacent the bottom thereof for supporting said post for swivelling movement, extensible means for normally holding said post in upright position, and a plurality of 55 pivoted members surrounding said post and supporting means.

11. A lamp post or similar structure having in combination, an upstanding post, a member having a curved surface secured to 60 the lower end thereof, extensible means for holding the said members normally in upright position and a movable supporting means adjacent the post operative to permit the post to be swung to substantially a hori- 65 zonal position.

In testimony whereof I affix my signature.
FRANK W. GRISWOLD.
